United States Patent

Des. 237,386
Patented Oct. 28, 1975

237,386

INCENSE BURNER

Thomas D. Tokunaga, 2116 Associated Road, Apt. B,
Fullerton, Calif. 92631

Filed Apr. 11, 1974, Ser. No. 460,094

Term of patent 14 years

Int. Cl. D31—00

U.S. Cl. D23—78

FIG. 4

FIG. 5

FIG. 6

FIG. 7

FIG. 1 shows a perspective view of my new and novel design for an incense burner;

FIG. 2 shows a cross section of my incense burner through lines 2—2 of FIG. 1;

FIG. 3 is a front elevation view thereof;

FIG. 4 is a side elevational view thereof the opposite side of which is identical;

FIG. 5 is a bottom plan view thereof;

FIG. 6 is a rear elevation view thereof; and

FIG. 7 shows a sectional view of my incense burner through a midline section thereof along lines 7—7 of FIG. 1.

The broken lines in FIG. 1 show the intended environment of the incense burner and are for illustrative purposes only.

I claim:

The ornamental design for an incense burner, substantially as shown and described.
